UNITED STATES PATENT OFFICE.

THEODORE F. KOTTER, OF HOLLIS, NEW YORK.

DESIGN FOR A DOLL.

Application filed March 30, 1923. Serial No. 5,646. Term of patent 3½ years.

To all whom it may concern:

Be it known that I, THEODORE F. KOTTER, a citizen of the United States, residing at Hollis, Long Island, New York, have invented a new, original, and ornamental Design for a Doll, of which the following is a specification, reference being had to the accompanying drawing, forming a part thereof.

The figure of the drawing is a view in front elevation of a doll intended to represent a mammy with the features and different portions of the clothing of the mammy contrastingly colored.

I claim—

The ornamental design for a doll as shown and described.

In witness whereof I have hereunto signed my name this 1 day of March, 1923.

THEODORE F. KOTTER.
